CLAIM

I claim the ornamental design for a flip sight, as shown and described.

DESCRIPTION

FIG. 1 is a front elevation view of a flip sight in open position, showing my new design;

FIG. 2 is a left side elevation view thereof;

FIG. 3 is a right side elevation view thereof;

FIG. 4 is a top view thereof;

FIG. 5 is a rear-bottom perspective view thereof;

FIG. 6 is a rear elevation view thereof;

FIG. 7 is a front-top perspective view thereof;

FIG. 8 is a front elevation view of the sight in a folded position;

FIG. 9 is a left side elevation view thereof;

FIG. 10 is a right side elevation view thereof; and,

FIG. 11 is a top view thereof.

The broken lines in the drawings depict unclaimed portions of the flip sight only and form no part of the claimed design.
